(57) **CLAIM**

The ornamental design for an automobile body molding kit, as shown and described.

DESCRIPTION

FIG. 1 is a front perspective view of an automobile having the body molding kit according to my novel design;

FIG. 2 is a rear perspective view thereof;

FIG. 3 is a front view thereof;

FIG. 4 is a rear view thereof;

FIG. 5 is a left side view thereof;

FIG. 6 is a right side view thereof; and,

FIG. 7 is a top view thereof.

The broken line showing of an automobile is for illustrative purposes only and forms no part of the claimed design.
